(57) **CLAIM**

The ornamental design for a digital audio disc player for automobile, as shown and described.

DESCRIPTION

FIG. 1 is a right, front, and top perspective view of a digital audio disc player for automobile;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines in the drawings are for the purpose of illustrating portions of the digital audio disc player for automobile that form no part of the claimed design.
